UNITED STATES PATENT OFFICE.

ALBERT L. ROSEMOND, OF OBERLIN, OHIO.

RAIL-JOINT.

SPECIFICATION forming part of Letters Patent No. 722,907, dated March 17, 1903.

Application filed August 28, 1902. Serial No. 121,372. (No model.)

To all whom it may concern:

Be it known that I, ALBERT L. ROSEMOND, a citizen of the United States, residing at Oberlin, in the county of Lorain and State of Ohio, have invented a new and useful Rail-Joint, of which the following is a specification.

This invention relates to railway-rail joints, and has for its object the production of a device wherein the size of the rail is increased opposite the portions forming the joint to not only strengthen the joint, but also preventing the concussion from the passing trains deflecting the rails at the joints, and also relieving the tie-bolts from all shearing strains.

The invention consists in certain novel features of the construction, as hereinafter shown and described, and specified in the claims.

In the drawings illustrative of the invention, Figure 1 is a perspective view of one of the improved joints complete. Figs. 2 and 3 are perspective views of the adjacent ends of the rails disconnected. Fig. 4 is a transverse section through one of the tie-bolts. Fig. 5 is a bottom plan view.

The body portions of the rails are of the usual construction, consisting of the head-flanges 10, the vertical webs 11, and the tie-flanges 12, as shown. The head-flanges 10 are adapted to engage endwise, as illustrated in Fig. 1, and the vertical webs are extended in the form of overlapping tongues 13 14, the inner faces of the tongues arranged in vertical alinement with the centers of the vertical webs 11 and extended laterally, so that the tongue portions are thicker than the vertical webs, of which they are continuations. The tongue portions extend beneath the outer portions of the head-flanges, and the vertical webs are formed at the roots of the tongues with shoulders 15, against which the ends 16 17 of the respective tongues abut when the rails are united, as indicated in Fig. 1. Adjacent to the shoulders 15 the vertical webs are extended outward, as at 18, to correspond with the lateral extensions of the tongues 13 14, so that the outer surfaces of the tongues are gradually merged into the general surfaces of the webs.

The tie-flange 12 is divided centrally oppo-

site the tongue portions 13 14, as indicated at 19 in Fig. 5, and with the ends rounded, as at 20 19, and adapted to overlap, as shown in Fig. 5, when the two parts of the rail are united.

The adjacent faces of the parts 13 14 are formed with alternately disposed and interlapping grooves and channels 21 22, which interlock when the parts are united, as illustrated in Fig. 4.

The tongues 13 14 will be provided with spaced apertures 23 24, adapted to register when the parts are united and provide means for the transverse tie-bolts 25, as shown.

The tongue members 13 14 are extended vertically downward, and the portions of the tie-flange 12 opposite the tongues will likewise be extended downward, as shown, the adjacent ends of the tie-flanges upon the bodies of the rails being merged into them, as indicated. By this means the portions of the rails which form the joint are increased in size both laterally and vertically, so that when the tongues 13 14 are interlapped, with the head-flanges 10 10 abutting endwise, and the end of the tongues abutting against their respective shoulders 15, and the divided tie-flange interlocking along the line 18, and the tie-bolts 25 secured in place through the apertures 23 24, a joint of great strength is produced, which will not only effectually resist any deflecting strains from the passing trains, but will likewise resist any lateral or torsional strains.

It will be noted by reference to Fig. 4 that the vertical strains are borne entirely by the interlocking head members 10 and grooves and channels 21 22 and all shearing strains upon the bolts 25 entirely obviated. It will also be obvious that by increasing the thickness of the tongues 13 14, which are continuations of the vertical webs of the rails, the tendency to deflection at the joints is eliminated and the rails rendered as stiff and strong at the joints as at other points, thus securing practically a continuous rail and without the employment of additional clamping-plates, chairs, or other extra parts, the whole joint being formed with portions of the rail itself or formed integral with the rail.

The abutting shoulders 15, together with

the curved portions 20, are an important feature of the invention, as they receive the longitudinal strains and prevent end strains between the parts 10 10.

5 The apertures 23 24 will be elongated to provide for the necessary expansion and contraction.

10 The peculiar formation of the ends of the rails herein shown can be easily produced when the rails are manufactured by drop-forging, hammering, or by pressure, as may be preferred, so that the expense of the joint constructed in this manner may be much less than with joints constructed with extra clamp-15 plates or "fish-bars."

15 The improvement may be applied to any of the various sizes of rails.

20 The tongues 13 14 may be of any desired length and as many of the apertures 23 24 may be employed as required; but generally four will be sufficient, as shown.

25 As many of the interlapping grooves and channels 21 22 may be employed as required, and the parts may be modified and changed as to proportions and relative sizes of the parts without departing from the principle of the invention or sacrificing any of its advantages. By this arrangement of joint the overlapping portions may be coupled by placing 30 the overlapping portions side by side and then engaging them by bringing the parts together laterally, or the tongues 22 and the channels 21 may be engaged by their opposite ends and the rails united by sliding them together 35 longitudinally, as preferred, or as circumstances may require.

Having thus described the invention, what is claimed is—

40 1. A railway-rail joint consisting of overlapping tongues corresponding to the vertical webs and projecting beyond the head-flanges and reversely extended laterally, said tongues provided longitudinally with interlapping grooves and channels and having transverse

spaced apertures for the reception of the tie- 45 bolts, substantially as described.

2. A railway-rail joint consisting of overlapping tongues corresponding to the vertical webs and projecting beyond the head-flanges and reversely extended laterally, said tongues 50 provided longitudinally with interlapping grooves and channels and having transverse spaced apertures for the reception of the tie-bolts, and said rails having lateral extensions at the roots of said tongues and forming 55 shoulders to receive the abutting ends of the tongue of the opposite rails, substantially as described.

3. A railway-rail joint consisting of overlapping tongues corresponding to the vertical 60 webs and projecting beyond the head-flanges and reversely extended laterally, said tongues provided with longitudinally-disposed interlapping grooves and channels, and the tie-flange of said rails divided centrally opposite 65 said tongues and with their ends reversely curved to form abutting interengaging shoulders, and means for transversely connecting said tongues, substantially as described.

4. A railway-rail joint consisting of overlapping tongues corresponding to the vertical webs and projecting beyond the head-flanges and reversely extended laterally, said tongues 70 provided longitudinally with interlapping grooves and channels, and the tie-flanges of 75 said rails extended vertically and divided centrally opposite said tongues, whereby the sizes of the rails are increased opposite said tongues, and means provided for transversely connecting said tongues, substantially as de- 80 scribed.

In testimony that I claim the foregoing as my own I have hereto affixed my signature in the presence of two witnesses.

ALBERT L. ROSEMOND.
